UNITED STATES PATENT OFFICE

1,996,456

HAY-CARRIER

William Carter, Milwaukee, Wis.

Application January 29, 1934, Serial No. 708,821

1 Claim. (Cl. 212—61)

This invention appertains to barn equipment, and more particularly to an improved carrier, or conveyor, for distributing hay, or like material, into barns incident to the storing thereof.

5 Due to the large cattle herds of today, the building of large barns is a necessity. These large barns with their tremendous storage room require hay carrier equipment. The present equipment is of a high costly nature, running 10 into many hundreds of dollars, and the barns to a certain extent have to be specially built for the reception of the same.

Generally, the present equipment embodies a longitudinally extending steel track paralleling 15 the ridge pole of the roof with special bracing, and a carrier slidably mounted on the track for receiving the hoist for the hay sling, or grapple hooks. Not only is the initial cost of this equipment large, but the installation cost is very high, 20 as is also the operating cost.

It is, therefore, one of the primary objects of my invention to provide a hay-carrier, or hoist, particularly adapted for use in barns, which will be inexpensive to manufacture and install, one 25 that will be easy to manipulate, and one which will be of an exceptionally simple and rugged character, capable of withstanding heavy loads.

Another salient object of my invention is the provision of a hay-carrier and hoist, embodying 30 a swinging boom for receiving the hoist rope with novel means for mounting the boom in the roof of the barn, whereby the load will be effectively supported by the roof rafters to permit the easy rotation or swinging of the boom from one end 35 of the barn to the other.

A further object of my invention is the provision of novel means for mounting the hoist rope for the hay sling relative to the boom and the mounting for the boom, whereby a direct pull can 40 be obtained on the hoist rope for effectively manipulating the same.

A further object of my invention is the provision of novel means for bracing the boom relative to the mounting for the boom, whereby free 45 swinging movement of the boom around its mounting is assured.

A further object of my invention is the provision of novel means for handling the boom, whereby a single operator can effectively actuate 50 the hoist rope, as well as move the boom to the desired position with the load.

A still further object of my invention is the provision of novel means for constructing the hay sling to be utilized with the hoist rope, whereby 55 the sling can be utilized for handling an entire

wagonload of hay, with novel means for breaking the sling, so that the load can be readily dumped.

A still further object of my invention is the provision of novel means for forming the sling, whereby the hay is prevented from becoming entangled with the ends of the sling, whereby to insure the dropping of the entire load. 5

With these and other objects in view, the invention consists in the novel construction, arrangement and formation of parts, as will be 10 hereinafter more specifically described, claimed and illustrated in the accompanying drawings, in which drawings:—

Figure 1 is a central transverse section through a conventional barn construction, showing my 15 improved hay-carrier incorporated therewith.

Figure 2 is a fragmentary side elevation of my improved hay-carrier drawn on a larger scale, parts of the carrier being shown broken away, and in section to illustrate structural details. 20

Figure 3 is a fragmentary side elevation of a slightly modified form of my improved hay-carrier, which is adapted to be used in barns of smaller capacity, parts of the carrier being shown broken away and in section. 25

Figure 4 is a bottom plan view of my improved hay-sling. 30

Figure 5 is an enlarged fragmentary transverse section through the hay-sling, taken substantially on the line 5—5 of Figure 4, looking in 35 the direction of the arrows.

Referring to the drawings in detail, wherein similar reference characters designate corresponding parts throughout the several views, the letter A generally indicates my improved hay-carrier, and B a barn in which the same can be installed. 35

The barn B can be of any preferred character or construction; and, as shown, the same includes the front and rear walls 10 and 11, the side walls 12, and the roof construction 13. The front wall 10 is provided with a central doorway 14, having an inclined runway 15 leading thereto. 40

The roof 13 has been shown to be of the double pitch (mansard) type, and includes the usual ridge pole 16 supported by the rafters 17 and purlines 18. The lower terminals of the bottom rafter 17 may rest upon a roof plate 19, and tie- or cat-beams 20 can extend across the barn. 45

My improved hay-carrier A comprises a boom 21, the body portion of which can be of a solid base of wood. The upper end of the body of the boom can have bolted thereto bearing plates 50

22 for supporting the top pulley 23 for the hoist rope 24. The lower end of the boom can have bolted thereto bearing plates, or arms, 25.

Obviously, the boom can be constructed in other manners without departing from the spirit or the scope of my invention.

The boom 21 is carried in a novel manner by one of the tie-, or cat-beams, 20 of the barn, which is preferably disposed adjacent to the doorway 14. The means for mounting the boom in place on the tie-beam 20 consists in the use of base, or supporting, plate 26, which can be in the nature of a casting.

This base, or supporting, plate 26 is placed directly on top of the tie-beam 20 adjacent to one side of the barn, and the longitudinal edges of the plate 26 can be provided with depending side flanges for gripping, or engaging, the side faces of the beam to prevent shifting of the plate. Suitable bolts 27 are employed for firmly securing the plate 26 in position.

Formed on the plate 26 is a hollow stud, or post, 28, the purpose of which will be later set forth. It is to be noted, however, that the outer face of this hollow stud, or post, 28 can be provided with external threads adjacent to its upper end. Rotatably mounted upon the stud, or post, 28 in superimposed relation to the base plate 26 is a turntable plate 29. Suitable anti-friction bearings are placed between the base plate 26 and the turntable plate 29. Lock nuts 31 are threaded on the post 28 in order to hold the turntable plate 29 in proper position.

Formed on the upper face of the turntable plate 29 at one side of the post 28 are a pair of upstanding bearing arms, or ears, 32. These bearing arms, or ears, 32 rotatably support the lower sheave, or pulley wheel, 33, and it is to be noted that part of the periphery of the pulley wheel 33 overhangs the post 28, and the post 28 is disposed substantially tangentially to the periphery of the pulley.

The bearing arms 25 of the boom 21 straddle the bearing ears 32 below the pulley wheel 33 and are connected to bearing ears 32 by means of a transversely extending pivot bolt, or shaft, 34.

Rockably mounted on the shaft, or pivot bolt, 35 which supports the uppermost pulley wheel 23 is a yoke 36. This yoke 36 carries an eye 37, to which is secured a guy, or brace, rope 38. The lower end of the guy rope 38 is secured to an eye 39 carried by one of the side purlines 18. It is to be noted that the eye 39 is directly above the hollow post 28, and the eye and post are in direct vertical alinement.

The hoist rope 24 is trained over the pulley wheels 23 and 33, and is extended through the hollow stud 28 and a guide opening 40 formed in the tie-beam 20. This end of the hoist rope is secured to and coiled about the drum 41 of a winch 42. This winch 42 may be of any preferred construction, and is carried by the floor of the barn at one side of the door opening 14.

65 The portion of the hoist rope which extends down from the pulley wheel 23 carries a suitable hook which is adapted to be connected with the middle rings of the sling chains 43.

As stated in the objects of the specification, 70 the sling, indicated by the reference character 44, is of a novel construction, and the sling is arranged so as to extend over the entire area of the bed of a hay wagon, so as to support the entire load. This sling 44 includes companion sections 45 and 46.

The sections 45 and 46 each include inner angle irons 47, and outer longitudinally extending straps 48. Transversely extending bed straps 49 are riveted to the angle irons 47 and the longitudinally extending straps 48.

The sling chains, or ropes, 43 are adapted to be carried by the outer longitudinally extending straps 48, and by referring to Figure 4 of the drawings, it will be noted that the outer terminals of the bed straps 49 extend beyond the longitudinal straps 48 and have their terminals provided with downwardly bent extensions 50. I lay particular stress on the bent-down extensions 50 in that these extensions effectively prevent the hay from tangling with the sling, and also form means for slightly spacing the sling from the bed of the haywagon.

The abutting angle irons 47 are releasably connected in a novel manner so that when the load has reached the desired position the sections 45 and 46 can be disconnected to permit the dropping of the load.

The means for detachably connecting the sections consists of spaced eyes 51, carried by one angle iron 47, which are adapted to extend through openings 52 formed in the other angle iron. Releasable latch levers 53 and 54 are pivotally carried by the angle iron having the openings 52 for releasably engaging the eyes 51.

The latch levers 53 are rockably mounted intermediate their ends, as at 55, on their angle bar 47, and terminate in overlapping relation at the longitudinal center of the sling, and are rockably connected at this point to a common yoke 56, to which is secured the release, or trip, 35 rope 57.

The outer ends of the latch levers 53 and 54 are provided with bills 58 which extend into the eyes 51. Obviously, when the sling is under load and pull is exerted on the release rope 57, 40 the latch levers 53 and 54 will be raised at their outer ends above the eye 51, whereby the weight of the load is allowed to spread the sections 45 and 46 of the sling.

In use of my improved carrier, the loaded wagon with the sling in place is driven into the barn and the guide, or drag, rope 59 is manipulated so as to dispose the boom 21 directly over the wagon. The drag, or guide, line 59 is preferably secured to an intermediate portion of the boom, which facilitates the manipulation of the boom.

The hoist rope 24 is now slackened by the use of the winch, and the hook is connected to the middle rings of the sling, after which the winch is operated to raise the load off the wagon. When the load reaches the desired height the dragline 59 is manipulated so as to rotate the boom around the hollow stud 28 until the load reaches the desired position, after which the release rope, or cable, 57 is actuated to permit the dropping of the load.

Due to the construction of the boom and its mounting, the hoist rope is effectively guided and the strain from the boom is effectively distributed to the boom mounting, in view of the fact that the pivot ears 32 are arranged in close proximity to the hollow stud 28.

As the eye 39 is located directly above the stud, the free swinging of the boom around the 70 stud is permitted. If preferred, the guy rope 38 can be made adjustable so that the boom can be raised and lowered.

In Figure 3 I have shown a slightly modified form of my invention, which is particularly 75

adapted for use in barns of small construction, or that type of barn having a single pitch (hip) roof construction.

This modified form of carrier is generally indicated by the reference character C and embodies a rugged hollow standard 60, having formed thereon a base 61 which is bolted to the desired tie-beam. The upper end of the hollow standard 60 has formed thereon, or secured thereto, a cap plate 62.

This cap plate 62 in turn has formed thereon at its axial center the hollow post, or shaft, 83. Rotatably mounted on the cap plate 62 is a turntable plate 64. Suitable anti-friction bearings can be interposed between the cap plate 62 and the turntable plate 64. A nut 66 of the desired form is threaded on a hollow post 63 for holding the turntable plate in position. Secured to the post 63 above the holding nut 66 is a collar 67 having secured thereto brace rod 68, which can be bolted, or otherwise secured, to adjacent roof rafters 69.

The boom 70 can be of substantially the same construction as that illustrated in the preferred form of my device, and the lower end of the boom is connected by means of a cross bolt 80 to ears 81 formed on the turntable plate 64 adjacent to the post 63.

The outer end of the boom 70 carries the top pulley wheel 71 and adjacent to its lower end carries the lowermost pulley wheel 72, and it is to be noted that the post 63 is tangentially disposed with reference to the pulley wheel 72.

In order to brace the boom diverging brace rods 73 are secured to the outer end thereof, and the lower ends of these brace rods 73 are bolted, or otherwise secured, to a rotatable ring, or collar, 74 mounted upon the standard 60. The standard 60 is provided with a thrust flange 75 for supporting the weight of said ring, or collar.

This carrier is actuated in the same manner described for my carrier A, and it is to be noted that the hoist rope 76 is trained over the pulley wheels 71 and 72 and thence threaded through the hollow post 63, the hollow standard 60, and through an opening formed in the roof rafter.

If preferred, a platform 85, shown in dotted lines in Figure 2, can be built on the turntable plate 29 for supporting an overhead winch 86, so that the hoist rope can be operated from above. In this instance the plate 29 can be built on a larger scale to receive the platform.

From the foregoing description, it can be seen that I have provided an exceptionally simple and durable appliance for facilitating the storing of hay and like material in barns, which entirely eliminates the complicated and costly track structure heretofore used.

Changes in details may be made without departing from the spirit or the scope of my invention, but what I claim as new is:—

A hay-carrier and hoist for barns comprising, a hollow standard having an attaching base and a flange directly above said base, a cap plate secured to the upper end of the standard having an axially disposed hollow post, a turntable plate rotatably mounted on the cap plate and post, a boom hingedly secured at its lower end to the turntable plate at one side of the hollow post, a collar rotatably mounted on the standard and resting on said flange, bracing arms pivotally connected to the collar and extending from said collar to the outer end of the boom, pulley sheaves disposed adjacent to the opposite ends of the boom, a hoist cable trained over the pulley sheaves and threaded through the post and standard, and a brace rod connected directly to the upper end of the post above the turntable plate and adapted to be secured to a roof rafter.

WILLIAM CARTER.
